PROCESS OF PREPARING WARP

Alexander Bruenn, New York, N. Y.

Application May 16, 1932, Serial No. 611,723

2 Claims. (Cl. 28—22)

My invention relates to a preparation of threads to be used in a weaving machine and refers more particularly to the process of preparing warp.

One object of my invention is to provide a means for applying a cohesive or adhesive to warp threads so as to increase the strength of the threads and prevent excessive breakage during the process of weaving. I will thus increase the cohesive strength of the material as well as pre-10 serve its elastic quality.

A further object of my invention is to provide a process of preparing the threads making up a warp thread by first treating the threads with a preparatory softening solution of oil emulsion 15 in skein form, before winding, in a tub or container, and then passing the threads through a cohesive solution of a colloidal nature, and thereafter drying the threads, which process increases the strength of the individual warp threads.

20 A still further object of my invention is to provide a means for the treatment of warp threads, so that in the process of weaving, a weaver can tend a great number of looms, more than it is possible to take care of at the present 25 time, due to the fact that there will be less breakage in the warp threads.

I attain these objects preferably by the means illustrated in the accompanying drawing, wherein similar numerals refer to like parts throughout 30 the several views, in which:—

Figure 1 is a diagrammatic view of the means used in treating the warp threads.

Figure 2 is a diagrammatic view, illustrating how the warp threads are wound upon the warp 35 beam.

The device is comprised of a frame 1, upon which are mounted a multiple of spools, indicated by 2, 3, 4, 5, 6 and 7, but it is obvious that this spool frame may contain any multiple of spools 40 desired, as the drawing indicates this number of spools for the sake of illustration only.

The threads from these spools pass over a roller 8, through a stop motion 9, then through a reed 10, and from this reed, the threads pass over a roller 11, under a roller 12, over a roller 13, and there is a receptacle 14, underneath the aforesaid 45 rollers, that contains a cohesive solution of a colloidal character 15, and the threads pass through this solution.

50 These threads originally were treated to a preparatory softening solution before being wound on the spools 2 to 7, inclusive, so that the cohesive solution in the tank 14 will adhere to the threads.

After the threads leave the roller 13, they pass 55 through a gatherer 16, for the purpose of bring-

ing the threads together, so that they will adhere to each other.

This gatherer is necessary to bring the threads together after they have been softened and immersed in colloidal solution to compel the threads 60 to join into a unitary structure.

After leaving the gatherer, the threads pass through a heating chamber 17, to which heat may be applied through the steam pipe 18, or by any other suitable means, and as these threads 65 are passed through the heating chamber 17, the cohesive solution is dried, and the threads then pass through the lease reed 19, and are wound upon the section beam 20.

A multiple of these section beams 20 are suitably mounted upon a frame 21, from which they pass through the lease reed 22, and are thereafter wound upon the warp beam 23, from whence 70 they are utilized in weaving machines.

The reason for taking the prepared threads and 75 immediately putting them onto a section beam so as to create a warp, is as follows:—As the material has to be put into a warp it is cheaper to make it directly onto a warp instead of first making it onto a spool; and furthermore, when these 80 threads are being prepared into the condition desired by putting them immediately onto the warp or beam the material handled will be rolled up evenly and the tension on the individual thread will be kept normal and steady, whereas, 85 had this been put onto a bobbin and then made into a warp the tension and the evenness would be changed causing streaks in the cloth when woven.

Having thus illustrated and described the preferred embodiment of my invention, I do not wish to limit myself to the exact construction and arrangement of parts shown, since it is evident that modifications may be made therein, without departing from the spirit of the invention or 90 scope of the claims.

I claim:—

1. The process of preparing warp threads by treating the threads making up the warp that are wound on spools with a preparatory softening 100 solution, placing the spools on banks, passing the threads thus treated through a stop motion, then through a reed, passing the threads under a roller, through a colloidal solution gathering the threads in a gatherer in groups to unite them into individual threads, drying the threads, passing the threads through a lease reed, and then winding the threads upon a section beam.

2. The process of preparing warp threads by 105 treating the threads making up the warp that

are wound on spools with a preparatory softening solution, placing the spools on banks, passing the threads thus treated through a stop motion, then through a reed, passing the threads under a roller, 5 through a colloidal solution, gathering the threads in a gatherer in groups to unite them into individual threads, drying the threads, passing

the threads through a lease reed and then winding the threads upon a section beam, placing a multiple of section beams upon a bank, passing the threads through a reed and winding the threads upon a warp beam.
